CLAIM

The ornamental design for a rowing exercising machine as shown and described.

DESCRIPTION

The file of this patent contains at least one drawing/photograph executed in color. Copies of this patent with color drawing(s)/photograph(s) will be provided by the Office upon request and payment of the necessary fee.

1.1 is a front view of a rowing exercising machine showing my new design;

1.2 is a back view thereof;

1.3 is a left side view thereof;

1.4 is a right side view thereof;

1.5 is a top view thereof;

1.6 is a back perspective view thereof;

1.7 is a bottom view thereof;

2.1 is a front view of an alternative embodiment of the rowing exercising machine, with the top clamp in a collapsed position;

2.2 is a back view thereof;

2.3 is a right side view thereof;

2.4 is a left side view thereof;

2.5 is a top view thereof;

2.6 is a bottom view thereof; and

2.7 is a front perspective view thereof, with the top clamp in an extended position.

(Continued)

The broken lines in the figures depict portions of the rowing exercising machine which form no part of the claimed design.
